UNITED STATES PATENT OFFICE.

DELL LACY, OF WILMINGTON, OHIO, ASSIGNOR TO THE IRWIN AUGER BIT COMPANY,
OF WILMINGTON, OHIO, A CORPORATION OF OHIO.

METHOD OF CUTTING, SHAPING, AND POLISHING METAL ARTICLES.

1,415,879.

Specification of Letters Patent. Patented May 16, 1922.

Application filed April 1, 1920. Serial No. 370,404.

To all whom it may concern:

Be it known that I, DELL LACY, a citizen of the United States, residing at Wilmington, in the county of Clinton and State of Ohio, have invented certain new and useful Improvements in the Method of Cutting, Shaping, and Polishing Metal Articles, of which the following is a specification, reference being had therein to the accompanying drawing.

My invention relates to the method of cutting, shaping and polishing metal articles by the rapid rotation of a suitably shaped metal cutting and polishing metal wheel.

The object of my invention is to remove metal from a bar of stock to be converted into a bit. Although it is not necessary, I prefer to initially form the bit from a die in order to define by the impression made upon the bar of stock the areas which I am going to remove by my abrasion wheel and process of removal.

When a relatively fast moving hard surface which is highly polished moves against a somewhat softer and more or less roughened surface the fast moving surface will tend to drag the grain of the roughened surface and cut it away in minute chips or slivers of metal, the action being somewhat similar to that of a knife cutting a pencil. A grinding operation on the contrary, differs from the foregoing, in that the member being ground is usually about as hard if not harder than a grinding member when the hardness of the article as units as distinguished from the hardness of the particles composing it is considered.

In a grinding operation the individual grains of the grinding compound may be much harder than the individual portions of the article being ground, but as an article the grinding compound being of lesser strength than a group of such hard particles, wears away more quickly than the article being ground. In grinding it becomes a question of mutual abrasion with the surfaces of the articles abrading one another being broken up in fine particles and pulverized, thus resulting in the polishing of one of them and the gradual disintegration of the other.

In detail, my object is to remove metal from the stock, rough dress it and finally polish it by the same dressing wheel. My process has for its object the removal of

metal by a metal dressing wheel, rough dressing the metal and then polishing it. My method or process of producing a bit is to take a bar of stock, form it in the rough with a well-known type of die, place the bar of stock against the dressing wheel of steel, slowly revolving the bar of stock as the wheel is revolved and where necessary reciprocating the bar of stock to insure the removal of the metal in such locations on the bar of stock as may be desired.

Referring to Figure 1, this figure illustrates a side elevation of the wheel with a bit nearly completed in engagement with the dressing surface of the wheel.

Fig. 2, is a side elevation of the bar of stock with the point turned up and the shank roughly formed.

Fig. 3, is a side elevation of the bar of stock, Figure 2, after having received its initial treatment in the removal of stock.

Fig. 4, is a side elevation of the finished bit.

Referring to Figure 1, 1 is a shaft, 2 is a nut on the end of the shaft retaining the dressing wheel 3, which is made of steel. On the face of the dressing wheel 3 is projection 4 extending around its periphery and a similar projection 5. The size, shape and special configuration of these projections are of no importance save that they must be of a character suitable to remove the metal from the stock. The amount of metal to be removed and the size of the cut to be made will determine in each instance the character of the projection.

6 is the shank of the bit and 7 the twist; 8 is the head of the bit.

The method of operation is as follows: The wheel 3 is revolved and at the same time the bar of stock, which may either be stationary or may be revolved, is brought in contact with the wheel or its projections. A cutting compound may or may not be used, as desired. The stock is gradually removed by the rapidly revolving wheel. The bar of stock may be reciprocated back and forth as well as revolved, in order to insure the proper removal of the stock from the bar in such particulars as may be necessary to produce the bit, for instance: The depth of cut, the degree of finish and the speed of the operation may all be controlled by the speed of the moving parts, the nature of the cutting compound, and the relative hardness of the wheel and the bar of stock.

The cutting wheel of this character eliminates sizing the head, grinding the crimp, stemming, using a rubber wheel on the hollow, roughing the stem, smoothing the hollow and smoothing the stem. If it is desired also to treat the shank, then roughing the shank and its edges and the smoothing of the shank and its edges are steps which are also eliminated.

10 The hollow is that portion of the bit indicated by 9 and the stem is that portion indicated by 10.

Having thus fully described my invention, what I claim as new and desire to secure by 15 Letters Patent, is:

1. The herein described method of producing auger bits comprising forming a bar of stock, revolving and reciprocating the bar of stock against a rapidly revolving metal cutting wheel, the cutting wheel having configurations thereon adapted to act upon the stock to form the twist and the stem therebetween on said bar of stock, holding the stock in such relation to the wheel as the stock is turned and reciprocated so that a part of the configuration of the cutting wheel will form curved surfaces on the sides of the twist while other configurations of the wheel are simultaneously removing the 30 surplus part of the stock and continuing this same operation until the twist and stem are reduced to a proper shape and size.

2. The herein described method of producing auger bits comprising forming a

bar of stock, revolving and reciprocating the bar of stock against a rapidly revolving metal cutting wheel having configurations thereon adapted to coact upon the stock to form the twist and the stem therebetween on said bar of stock, holding the stock in such relation to the wheel as the stock is turned and reciprocated so that the configuration of the wheel will form surfaces on the side of the twist concave in shape while other parts of the wheel are simultaneously removing the surplus part of the stock until the stem is reduced to a proper cylindrical size, and polishing the bit so made with the same metal revolving wheel.

3. The method of producing auger bits 50 and the like comprising forming a bar of stock, revolving and reciprocating the bar of stock against a rapidly rovolving metal cutting wheel, the cutting wheel having configurations thereon adapted to act upon the stock to form the twist and the stem therebetween on said bar of stock, holding the stock parallel to the axis of the wheel as the stock is turned and reciprocated so that a part of the configuration of the cutting 60 wheel will form the twist while other configurations of the wheel will remove the surplus part of the stock and continue this operation until the twist and stem are reduced to a proper shape and size.

In testimony whereof, I affix my signature.

DELL LACY.
